PENCIL SHARPENER

Jesse Atwater Jackson, Pensacola, Fla.

Application May 31, 1944, Serial No. 538,129

10 Claims. (Cl. 120—90)

This invention relates to an improved pencil pointing or sharpening device employing two stacks of resiliently supported blades arranged so the sharp edges of one stack are facing or opposing but not touching the sharp edges of the other stack, with suitable holding and guiding pieces as shall be described hereafter, and the whole contained in a small box or enclosure. In use, the pointing or sharpening is accomplished manually by introducing the end of the pencil or pencil lead between the opposing rows of sharp edges and reciprocating in such a manner as to cause small chips to be cut or scraped from the pencil until a tapering point of the desired sharpness has been achieved. Two forms of the invention are shown in the accompanying drawing. The first embodiment, shown in Figures 1 to 5 inclusive, employs flat blades each sharpened on one of its long edges, with the two stacks resiliently supported at their backs and above and below by means of suitably shaped pieces of sponge rubber. The second embodiment, shown in Figures 6 to 9 inclusive, employs wire springs for the blades, each having a sharpened edge along part of its mid-length, with the wires suitably guided into two stacks having opposed blade edges arranged so the springing of the wires themselves provides the resilient support for the sharp edges.

Figure 1 is a plan view.

Figure 2 is a side elevation.

Figure 3 is a section on lines 3—3 of Fig. 1.

Figure 4 is an isometric view, partly cut away.

Figure 5 is a view of a spacer piece.

Figure 6 is a section of a modification taken on line 6—6 of Fig. 7.

Figure 7 is a section on line 7—7 of Fig. 6.

Figure 8 is an isometric view of a wire blade.

Figure 9 is an isometric view, partly cut away, of a second modification.

Figure 10 shows the most convenient position of the hand holding the pencil in using the device.

The blades 1 are shown in two stacks of twelve blades each with their sharp edges 2 aligned on both sides of a tapering or wedge shaped space 3 between them. Said space 3 is of such dimensions that the edges of the blades 1 must rub against the point of the pencil when it is introduced between them. Mutual alignment of all the blades about said space 3 is maintained by the tapering or wedge shaped portion 4 of the spacer pieces 5. Suitable notches 6 in the ends of each blade 1 provide short unsharpened surfaces which bear against portion 4 of spacer pieces 5. A light pressure against the back edges

of the blades is supplied by the sponge rubber backing pieces 7, to push the sharp edges against the point of the pencil in use, or to return blades 1 to alignment against pieces 5 whenever the pencil point is withdrawn after use.

By repeated reciprocating motion of the pencil in the vertical direction, the point can be brought to a tapering wedge shape, or if desired, the point may be made conical by rolling the pencil between 10 the fingers to rotate it on its vertical axis as the vertical reciprocating is done. The desired sharpness of the point is governed by the number of times the vertical reciprocating motion is done.

15 A sponge rubber cushion piece 8 at the top and a similar piece 9 at the bottom of the stacks of blades 1 facilitate the ease with which the device is used by permitting the stacked blades 1 to tilt slightly from their horizontal planes as the 20 pencil point is pushed into and drawn out of the space 3. This motion in actual use is very slight and serves to make easier the manual effort of pushing the pencil up and down. In practice it has been found possible to get as sharp a point 25 as can be desired on a very short length of protruding lead merely by tilting the pencil slightly out of vertical as it is reciprocated. The slight motions of the stacks of blades serve to permit the fine flakes of graphite to work between the 30 blades where they act as a sort of dry lubricant, the excess falling out at the bottom.

The box or enclosure is composed of the cover piece 10 and the bottom piece 11 which are designed to be pressed or punched out of cardboard or light sheet metal for ease and cheapness of manufacture. Pieces 10 and 11 are fastened together by means of clips, by crimping, or by any other suitable method of making a permanent connection all around the flanged rim or 40 edge indicated at 12.

The complete assembly of the parts 1 to 9 within the enclosure 10, 11 is mounted on a base 13, which is made heavy to give stability and is provided with the oval cavity 14 for catching the shavings or graphite chips cut from the pencil in use. The further purpose of the flanged rim indicated at 12 is to fit in a suitable mating groove in the base 13, said groove being continuously straight at one side as at 15, thus permitting 45 ready removal of the assembly 1 to 11 from the base 13 for cleaning accumulated refuse from the cavity 14. This method of fastening is simple and provides a firm connection between the assembly and its base. A curved spring 16 is placed 50 in a groove 17 in the base 13, and arranged to 55

project above the edge of the flanged rim of the assembly at point 18 to lock the parts in position. Spring 16 is designed to permit ready removal or replacement of the base 13.

Slots or openings at 19 in the cushion piece 8 and cover 10 are provided to permit introducing the point of the pencil into the space 3. Similar openings at 20 in the cushion piece 9 and bottom piece 11 permit the shavings or chips to fall into the cavity 14.

The blades for this embodiment could readily be shaped from old or used safety razor blades of the Gillette or Schick-Ejector type, or they could economically be made of a cheap grade of steel, heat treated for brittle hardness only, and not tempered. The well-known Gillette thin blade or blue blade with a long central slot, made under patents, Nos. 1,850,902, 1,809,327 and 1,876,906, are advantageous because they give greater resilience. These blades are of the double edged type and have a central opening to give greater resilience to the portion adjacent the cutting edge. The curved wire blades of Figure 8 may also be used just like the razor blades and with the central V as in Figure 3, although I prefer with this type of blade to have the retaining grooves 26 substantially vertical, in which case the V angle is reduced to zero. In Figure 9 a compromise is shown, the V angle here being slight but yet noticeable. The spacer pieces 5 could cheaply be stamped out of light gage sheet metal. The sponge rubber pieces 7, 8 and 9 could readily be cut from sheet stock material. The base 13 could either be cast of iron or brass or die-cast of a low grade alloy. All parts thus lend themselves to the economies of repetitive methods of manufacture.

The blades 21 are shown in two stacks of twelve blades each, with a sharpened edge along the mid-portion of each blade at 22. The ends of each blade are extended as at 23 providing for the desired resilience by means of the spring action of the wire. For clarity of detail in the drawing, the blades 21 are drawn as if made of square wire, although wire of circular section would be just as suitable and somewhat cheaper. The stacks of blades are positioned within a cylindrical enclosure piece 24 by means of guide blocks 25 which may be made of wood and are fastened to the enclosure piece 24 with cement or nails. Grooves 26 in the blocks 25 hold the ends of each blade 21 to keep the stacks of blades in proper alignment.

The enclosure piece 24 is designed to be made cheaply of compressed fiber tubing of a common commercial grade which can readily be cut and threaded on an automatic lathe. A cover piece 27 has a slotted opening 28 for introducing the point of the pencil between the blades. A distancing piece 29 supports the stacks of blades at the bottom, and has a hole 30 to permit the graphite dust or cuttings to fall into the cavity 31. The cover piece 27 and distancing piece 29 are designed to be made cheaply of pressed cardboard or light gage sheet metal and are fastened to the cylindrical enclosure piece 24 by means of common wire stapler clips or cement. The complete assembly, parts 21 to 30 inclusive is screwed into a heavy base 32 which encloses the cavity 31.

In use, the operation with the pencil is exactly as described for the first embodiment. The alignment of the opposing blade edges as shown in this embodiment eliminates the tapering space as shown at 3, but it will be apparent that such a space could readily be provided for in the de-

sign by making the enclosure 24 slightly larger and cutting the grooves 26 in the blocks 25 on a slight angle from the vertical, as in Fig. 9. In this connection it will also be apparent that the tapering space 3 in the first embodiment could be eliminated by making the portions 4 of the spacer pieces 5 parallel, and shaping the sponge rubber backing pieces 7 with parallel sides. Here, it might be necessary to sharpen the blades with a greater bevel on the upper sides to more readily permit the point of the pencil to slide between them, and this has been done with the second embodiment. In either case, the operation of the device is not materially affected by eliminating the tapering space and a tapering point will be produced, since, in reciprocating the pencil between the blades, the portions at and near the end must pass across more blade edges than portions higher up.

20 In the manufacture of the spring blades 21, the grade of steel need not be expensive and the heat treating operation should be a simple one, since a mild steel with spring temper also acquires a certain amount of skin hardness. Due to the 25 nature of the cutting edges desired, it should be preferable to do the heat treating after the edges are sharpened.

In Figure 10 a wide base 33 is shown. The 30 position of the hand in Figure 10 illustrates how the wide base suits the convenience of the user and also gives stability to the device. Such stability is advantageous if the device is to be portable. An obvious variation, if desired, would be to have the device fixed to the top of a drawing 35 board or desk, by making the base of light sheet metal with a flange for holding down with screws. A cup or cupped portion of the base could readily be included to perform the function of the cavity 14, or 31. Another variation would be to have the flange arranged so the device could be mounted in a hole in the desk top, or near the edge of a drawing board so the top surface of the cover 10 or 27 would be flush with the surface.

45 This device, as shown in either embodiment, should save time for the draftsman who must keep a sharp point all the time, but it could as readily be made larger and with more blades to enable sharpening the whole pencil, wood and all. Marking crayons and artists charcoal sticks 50 are other possible uses. To use the device, as shown, with the ordinary wooden pencil requires that the wood be cut away first with a pen knife or some other means. Many draftsmen like to use the type of pencil holder having a chuck or collet grip in the end, for which they procure 55 leads in various hardnesses, and for them the present device should be ideal. The feature of greatest value to the user is that this device is kept most handily near the pencil work being done, and therefore can be reached frequently to keep the pencil point at the desired sharpness without taking the eyes or the other hand from the work.

60 I claim as my invention:

1. In a device for pointing an object such as a pencil, the combination of a pair of stacks of opposed cutters, means for holding the stacks resiliently in position with the cutting edges of opposed cutters spaced progressively further apart to form a V, and means for limiting the approach of the cutting edges beyond the chosen angle defined by the progressive spacing.

2. The device of claim 1 in which the cutters are flat blades.

3. The device of claim 1 in which the cutters are curved wires.
4. The device of claim 1 in which the holding means engages a stack both below and at the rear of said stack.
5. The device of claim 1 in which each stack is composed of cutters held together merely by their frictional engagement with each other, whereby each single cutter has independent movement substantially normal to the sloping line of the cutting edges of the stack and against the resilient holding means.
6. The device of claim 1 in which the limiting means has opposite sloping edges of relatively unyielding material and all of the cutters engage said sloping edges with rubbing contact.
7. The device of claim 1 in which the blades are of the Gillette type and the limiting means is a pair of spaced patterns having sloping edges engaging all of the blades of each stack of cutters.
8. In a device for pointing an object, such as a pencil, the combination of a pair of stacks of
- 10 5 opposed cutters formed of centrally sharpened curved wires, means for holding the two stacks in position with the cutting edges of opposed cutters spaced progressively further apart to form a V and for limiting the approach of the cutting edges beyond the chosen angle defined by the progressive spacing.
- 15 10 9. In a device for pointing an object, such as a pencil, the combination of a pair of stacks of opposed cutters, means for holding the stacks in position with the cutting edges of opposed cutters aligned and for limiting the approach of the cutting edges beyond the margin defined by the cutting edges.
- 20 20 10. In a device for pointing an object, such as a pencil, the combination of a pair of stacks of opposed cutters, means for holding the stacks in position with the cutting edges of opposed cutters spaced progressively further apart to form a V, and means for limiting the approach of the cutting edges beyond the angle defined by the spacing which forms the said V.

JESSE ATWATER JACKSON.
